UNITED STATES PATENT OFFICE.

ALVIN M. YOCOM, OF POTTSTOWN, PENNSYLVANIA.

TANK CLOSURE.

Application filed November 7, 1922. Serial No. 599,528.

To all whom it may concern:

Be it known that I, ALVIN M. YOCOM, a citizen of the United States, residing at Pottstown, in the county of Montgomery and State of Pennsylvania, have invented 5 new and useful Improvements in Tank Closures, of which the following is a specification.

My invention relates to closures for liquid 10 receptacles, and is designed more particularly as an improved closure for gasolene tanks of automobiles, although, obviously, not limited to such use.

Its object is to provide a closure or cap 15 for such tanks, which will be more convenient to apply and remove than the caps in common use and which will have several additional functions besides that of merely closing the filling aperture, as hereinafter 20 set forth.

One of the features of my improved cap is the construction whereby it is quickly applied and removed; another is that it is locked against accidental removal; another 25 is that it also serves as a gage to indicate the amount of liquid in the tank, and still another is that it is so constructed that it constitutes a suction pump for withdrawing small amounts of liquid. In connection with 30 the cap construction, I preferably make use of a spring-actuated flap for automatically closing the filling aperture of the tank when the cap is removed.

The advantages of this device will be apparent 35 from the accompanying drawing, showing two forms of the invention and in which,

Fig. 1 is a vertical section through a liquid receptacle equipped with one form of the 40 cap, shown in elevation;

Fig. 2 is a vertical section on line 2—2 of Fig. 1, through the cap and on a larger scale;

Fig. 3 is a horizontal section taken on 45 line 3—3, of Fig. 2, looking upward;

Fig. 4 is a partial elevation and partial section through a slightly modified construction of the cap securing means;

Fig. 5 is a plan view of a modified form 50 of the invention, and

Fig. 6 is a vertical section of the same.

Describing these views in detail, 1 represents a liquid receptacle, for example, the gasoline tank of an automobile, provided with the usual filling aperture in its top, in 55 which aperture is secured the nipple 2, screw-threaded to receive the bushing 3. This bushing has a horizontal flange 4, which rests on the nipple or tank wall and is provided with serrations or teeth 5 on its upper 60 face, as in Figs. 1 to 4, or on its edge, as in Fig. 6. The bushing has an upwardly extending part or neck 6, from the top of which project two diametrically opposite segmental flange sections 7, the underside 65 faces of which are slightly oblique or inclined to constitute cam surfaces, as indicated by the dotted lines 8 in Figs. 2 and 6. In the form of cap shown in Figs. 1 to 3, these flange segments 7 extend inwardly 70 from the neck 6, while in the forms of Figs. 4 and 6, they extend outwardly. In Fig. 4 also, the nipple is shown as threaded externally and the bushing as threaded internally. In the form of Fig. 6, the nipple 75 2 is shown as integral with the tank. The closure consists of the cap member proper 10, the under face of which rests on the upper face of the segments 7, and which has a central hexagonal upwardly projecting 80 hub 11, and a downwardly projecting hub 12, bored out cylindrically from the under side to receive the cylinder 13. Said cylinder contains a piston 14, in the form of Fig. 2, or a float 34 in the form of Fig. 6, 85 the rod 15 of which passes through an opening in the top of the hub 11 and has attached to its upper end a knurled nut 16, in the form of Fig. 2, by which the piston can be manipulated. In said hole in the 90 hub 11, and surrounding said rod 15, is slidably mounted the sleeve 17, flanged at each end and surrounded within the cylinder by a coil spring 18, one end of which bears against the under face of the hub 11 and the other end against a washer 19, supported 95 by the flange on the lower end of said sleeve 17. Fitted on the hexagonal hub 11 and passed beneath the flange on the upper end of said sleeve 17, is a cup 20, the downwardly extending flange 21 of which has serrations or teeth 22 on its edge, adapted 100

to engage with the teeth 5 on the flange 4 of the bushing 3, thus locking the cap against accidental rotation. Surrounding the central hexagonal portion of said cap and secured thereto, as by spot welding at 23, is the handle member 24, suitably shaped, as at 25, to form a convenient grip. The underside of the cap 10 carries segments 30, the upper inclined faces of which engage 10 the inclined faces of the cam segments 7 to secure the cap in place. The segments 30 extend outwardly from a neck 31 in the form of Figs. 1 to 3, and inwardly from a flange 32 in the forms of Figs. 15 4 and 6. A flap valve 26, to close the filling aperture when the cap is removed, is, or may be, provided, and is shown as pivoted at 27 to the lower end of the bushing 3 or nipple 2, and as pressed to closing 20 position by a spring 28. The outside of the cylinder 13 is preferably graduated, as indicated at 33 in Fig. 1, to serve as a depth gage, but, in the form of Fig. 6, the float rod 15 is graduated instead. The lower 25 end of the cylinder is provided with a small opening 29 to admit the liquid to the cylinder. In the form of Fig. 6, the float 34, which fits loosely in the cylinder, is raised by the liquid entering the latter through 30 said opening 29, the graduations on the rod indicating the level or amount of the liquid in the tank. As it is not desirable that the rod should always be in raised position, means are provided on the cap handle 24, 25, 35 to hold said rod depressed except when it is used as a gage. This means consists, as shown, of a slide 35, slotted to engage rivets 36, mounted in the handle flange 25, and having a central depressed inclined portion 40 37, provided with an opening 38 through which the rod 15 can rise. It will be obvious that the details of mechanical structure may be varied somewhat, without departing from the spirit of my invention; for instance 45 mutilated screw-threads of the breech-block type would be the equivalent of the segmental cam flanges 7 and 30.

The mode of use of the device is as follows:

50 The cap being in the position of closure illustrated, to remove it the operator pulls upwardly on the handle 24, 25, thereby raising the locking cup 20 against the pressure of the spring 18, the hexagonal central portion of said cup sliding on the hexagonal hub 11 of the cap 10. This releases the teeth 22 on said cup from engagement with the teeth 5 on the flange 4 of the bushing 3. The cap is now given a quarter turn to the left, which 55 60 brings the cam segments thereon into the spaces between the cam segments 7, whereupon the cap can be lifted off the filling aperture, which is at once closed by the flap valve 26. The scale 33 on the cylinder, or on the

float rod, will indicate the amount of liquid 65 present in the tank. If a small amount of the liquid is wanted for any purpose, for example, some gasoline to prime the cylinders or for cleaning purposes, the pump piston 14 is drawn upwardly by means of the finger nut 16, before the cap is removed or the float, after having been allowed to rise by moving the slide 35 to bring the opening 38 over the rod 15, is then depressed again so that the taper end of said rod closes the 70 opening 29 in the bottom of the cylinder 13, thereby trapping some of the liquid in said cylinder, from which it can be ejected as desired.

Having thus described my invention, what 80 I claim is:

1. A tank closure, comprising a bushing secured in the filling aperture of the tank and having segmental cam projections thereon, a cap having conjugate segmental projections thereon, whereby the cap can be released from the tank by a partial rotation, locking teeth on said bushing, a locking member, carried by said cap and capable of a limited vertical movement relative thereto to be engaged with or disengaged from said teeth, a spring to resist said movements, and means to raise said locking member against said spring and to thereafter turn said cap and finally lift it off. 95

2. A closure for liquid receptacles, comprising an interrupted inclined surface around the filling aperture thereof, a cap having a conjugate interrupted inclined surface, spring-pressed locking means on said cap to prevent its accidental rotation, and a handle yieldingly connected to said cap to disengage said surfaces. 100

3. A closure for liquid receptacles, comprising an interrupted cam surface around the filling aperture thereof, a cap having a conjugate interrupted cam surface, spring-pressed locking means on said cap to prevent its accidental rotation, a handle secured to said locking means and non-rotatably mounted on said cap but capable of a limited longitudinal movement relatively thereto, and a spring resisting said longitudinal movement. 105

4. A closure for gasoline tanks of automobiles, comprising a cap having a mutilated cam surface connection with said tank around the filling aperture thereof, a locking member slidably mounted on said cap, a handle secured to said locking member, and a spring resisting the said slidable movement of said locking member and handle. 110 115

5. A closure for gasoline tanks of automobiles, comprising a cap having a mutilated cam surface connection with said tank around the filling aperture thereof and a central polygonal upstanding hub, a cup 120 125 slidable on said hub and provided on its

edge with locking means to prevent accidental rotation thereof, a sleeve passed through a central hole in said hub and having flanges on its ends, the upper one of which rests on the center of said cup, a spring between the lower flange of said sleeve and the under face of said hub, and

a handle secured to said cup, whereby the latter is first raised to release said locking means, whereafter the cap can be rotated to 10 disengage said cam surfaces.

In testimony whereof I have hereunto set my hand.

ALVIN M. YOCOM.
